UNITED STATES PATENT OFFICE.

JOHN J. KENNEDY, OF NEW YORK, N. Y.

METHOD OF SHORING EXCAVATIONS.

1,105,145.

Specification of Letters Patent.

Patented July 28, 1914.

Application filed January 7, 1913. Serial No. 740,701.

To all whom it may concern:

Be it known that I, JOHN J. KENNEDY, a citizen of the United States, and resident of the borough of Manhattan, in the city and State of New York, have invented a new and useful Improvement in the Method of Shoring Excavations, of which the following is a specification.

This invention relates to a method of shoring excavations contemporaneously with the digging thereof, with the object in view of providing arrangements whereby the necessity of breaking the ground for a much larger area at the surface than the desired cross section of the bottom of the excavation may be obviated.

Another object is to provide a method in which the apparatus may be very cheaply constructed and easily handled whereby great saving may be obtained in labor cost with complete protection for the men within the excavation.

It has previously been the custom in making excavations to start at the top a hole of much greater cross sectional area than that required for the bottom of the excavation, in order that the walls will be self-supporting to a large extent during the digging operation. Therefore, a great amount of earth has been customarily removed in excess of that required for opening up an excavation of the desired area. Furthermore, it has previously been difficult to adequately shore the walls of excavations except at considerable intervals during their formation. With these thoughts in mind, I have devised the method which comprises this invention.

A practical embodiment of the apparatus used in carrying out the invention is represented in the accompanying drawings, in which,

Figure 1 represents a top plan view of an excavation with the shoring in place. Fig. 2 represents a vertical section taken in the plane of the line A—A of Fig. 1, looking in the direction of the arrows. Fig. 3 represents a perspective view of part of the shoring in assembled position. Fig. 4 represents detail perspective views of the two kinds of planks used in forming the walls of the shoring, and Fig. 5 represents a detail interior perspective view of the shoring in assembled position, parts being broken away.

The walls of the shoring consist of series of planks 1, 2, 3, 4. These planks have their ends notched in order to be fitted together;

opposite planks 1 and 3 having the lower portions of their ends notched as at 5, 6, while the opposite planks 2 and 4 have the upper portions of their ends notched as at 7, 8, thereby forming two series of planks having notched ends for the purpose of enabling the planks to fit closely together in the form of a rectangle. Any number of tiers of these planks may be placed one upon another, as shown in Figs. 2, 3, and 5, according to the depth of the excavation, the planks forming a complete sheathing or covering for the walls of the said excavation.

As a further means of bracing the series of planks 1, 2, 3, 4, I provide vertical posts 9, adapted to fit inside the rectangle formed by the planks at the juncture of the ends of adjacent planks. These posts 9 may conveniently be composed of scantling or beams, oblong in cross section, arranged in double thickness with the broad faces touching each other, as clearly shown in Fig. 5, care being taken to "break joints", or, in other words, have the abutting ends of the scantling in one layer or thickness covered by the body of a scantling in the other layer, as clearly shown at 10, in Fig. 5. These uprights 9 may conveniently be held in position by horizontally disposed braces 11, fitted to be forced between adjacent uprights 9, at convenient intervals.

It will be seen that this structure is such that heavy pressure from the outside will only cause the bracing within to more effectively hold and support the sheathing or shoring composed of the series of planks 1, 2, 3, 4.

In case of work being carried on in sandy soil, it may be desirable to place bearers 12 at the bottom of the shoring.

The method of using this apparatus may be simply described as follows. The cross sectional area of the excavation desired being determined, ground is broken corresponding with that area, and after a hole several inches or more in depth has been dug, two planks 1 and 3, with the lower portions of their ends notched, are horizontally arranged on edge opposite each other in the excavation. The digging is then proceeded with until sufficient earth has been removed to permit of two planks similar to those denoted by 2 and 4 in the accompanying drawings, having the upper portions of their ends notched, being placed on edge at the other sides of the hole, with their projecting ends

under the projecting ends of the planks 1 and 3, as clearly shown in Fig. 3. Wedges 13 of wood or other convenient material, are then driven horizontally into the earth underneath and touching the planks 2, 4. The earth may then be removed from under the planks 1 and 3, for a considerable distance, during which operation the planks 2 and 4 will support the planks 1 and 3 by reason 10 of the engagement of their notched ends. After sufficient earth has been removed from under planks 1 and 3, planks exactly similar thereto are placed underneath them, and the wedges 13 removed from under the 15 planks 2, 4, and placed under this second tier of planks 1, 3. The earth may then be removed from under the planks 2, 4, while the latter will be supported by the second series of planks 1, 3, because the ends of the 20 latter project under the said planks 2, 4, and the wedges firmly support the said second series of planks 1, 3. It will be obvious that another set of planks like 2, 4, may then be placed in position under the first set of 25 planks 2, 4, and the wedges inserted beneath them, in which position they will be fitted to support the whole structure as thus far made. This cycle of operations may be repeated indefinitely, until the proper or desired depth of the excavation has been 30 reached. At desired intervals, the uprights 9 may be arranged in position and braced by the cross braces 11.

It will be seen from the above description 35 that the hole or excavation will be shored contemporaneously with the digging thereof, and that it will not be necessary to remove any earth other than that exactly needed for producing the cavity wanted.

40 If it seems desirable, the bearers 12 may occasionally be placed under the wedges 13 for the purpose of firmly holding them in soft ground, but this will, of course, depend upon the nature of the soil present during 45 the operation.

From the above description, taken in connection with the drawings, it must be evident that the apparatus is extremely simple and cheap to construct; while the method 50 may well be carried out by relatively unskilled labor; the shoring forming at all times a complete protection against caving in.

I contemplate that various changes may 55 be resorted to in the form, construction and arrangement of the several parts used in carrying out the method, without departing from the spirit and scope of my invention; hence I do not wish to limit myself strictly 60 to the form herein shown and described, but, What I claim is:

1. A method of shoring excavations as made, involving the following cycle of operations: first, placing a set of planks having notched ends opposite each other near 65 the top of the excavation; second, placing another set of planks, having similarly notched ends, opposite each other with their ends under the ends of the first mentioned set; third, placing supports under the second set of planks; fourth, removing the earth from under the first set of planks; fifth, placing a set of planks like the first set under the first set, and sixth, withdrawing the supports and placing them under the 75 last set.

2. A method of shoring excavations as made, involving the following cycle of operations: first, placing a set of planks having notched ends opposite each other near 80 the top of the excavation; second, placing another set of planks, having similarly notched ends, opposite each other with their ends under the ends of the first mentioned set; third, placing wedges under the second 85 set of planks; fourth, removing the earth from under the first set of planks; fifth, placing a set of planks like the first set under the first set, and sixth, withdrawing the wedges and placing them under the last 90 set.

3. A method of shoring excavations as made, involving the following cycle of operations: first, placing a set of planks having notched ends, opposite each other near 95 the top of the excavation; second, placing another set of planks, having similarly notched ends, opposite each other with their ends under the ends of the first mentioned set, and thereafter continuously supporting 100 all the planks by alternately placing temporary supports under certain of the planks.

4. A method of shoring excavations as made, involving the following cycle of operations: first, placing a set of planks having notched ends, opposite each other near 105 the top of the excavation; second, placing another set of planks, having similarly notched ends, opposite each other with their ends under the ends of the first mentioned set, and thereafter continuously supporting 110 all the planks by alternately placing a pair of temporary supports under opposite planks.

In testimony, that I claim the foregoing 115 as my invention, I have signed my name in presence of two witnesses, this twenty-second day of October 1912.

JOHN J. KENNEDY.
